TOOTH BRUSH

Alfred Arnegger, Remscheid-Lennep, Germany

Application March 7, 1934, Serial No. 714,512
In Germany March 14, 1933

1. Claim. (Cl. 15—136)

This invention relates to tooth brushes of that type in which the handle is hollow and is provided at one end with a rubber ball and at the other end with apertures which are located on the side 5 of the bristles and serve to supply a disinfecting or other liquid to the teeth while these are cleaned by means of the tooth brush. With the known constructional forms of tooth brushes of said type by far more attention had been paid to ejecting 10 the disinfecting liquid out through said apertures than to supplying the rubber ball and the hollow handle with said liquid in a convenient manner. In no instance is it possible to mix the dentrifrice in a glass and take it into the brush within 2 to 3 15 seconds without leaving any residue behind.

The object of the present invention is to overcome these drawbacks and to warrant likewise a powerful discharge of the disinfecting liquid through the said handle bores. I attain the object in view by providing at the free end of the handle, or at the respective end of the handle passage respectively, at least one opening which communicates with said passage and contains a non-return valve which establishes the communication 25 when the liquid is being sucked in, and interrupts said communication when the liquid is being forced out through the handle bores. It is now quite easily possible to suck the liquid from a glass quickly and conveniently, as well as to supply the bristles with the same, the sucking action and the pressing action being effected in both cases by means of the rubber ball.

The invention is illustrated diagrammatically and by way of example on the accompanying drawing on which Figure 1 is an axial section through a tooth brush designed according to this invention. Figure 2 is a horizontal longitudinal section through the free end of the handle where there is the non-return valve, this figure being drawn to a greatly enlarged scale relatively to Fig. 1. Figure 3 is an end-view of the handle and shows, besides, a slightly modified constructional form. Figure 4 is a view similar to Fig. 1 and shows likewise a slightly constructional form, other than in Fig. 3, and Figure 5 is an end-view of Fig. 4, thus, in so far, similar to Fig. 3, but drawn in the same scale as Fig. 4.

Referring to Figs. 1 and 2, *a* denotes the rubber ball, *f* the tubular handle, *g* that portion of the same to which the bristles *h* are attached, and *c* are perforations or bores through which the disinfecting liquid is supplied to said bristles and which are distributed among the same. The 55 bores *c* communicate with a passage *b* which ex-

tends through the entire length of the handle, from the rubber ball *a* to an aperture *e*, which is located at the free end of the handle and contains a non-return valve *d* which is of conical shape in the example shown in Fig. 2.

The portion *g* of the handle may be of oblong transverse section, for instance as shown in Fig. 3, and there may be a plurality of apertures *e*, each of which is provided with a non-return valve having either the same shape as in Fig. 2 or another shape.

Instead of conical shape, the non-return valve or valves may be of globular shape, as in the modification shown in Fig. 4 in which *f* denotes the valve ball which is located in the conical portion of the aperture *e*. A transverse pin *i* prevents the valve ball from being moved away too much from its seat.

In this constructional form the outlet bores for the liquid are located not between the bristles, but at the end proper of the handle. *k* denotes these bores, of which there is a plurality arranged side by side, as appears from Fig. 5. This arrangement of said bores presents the advantage that even the smallest residue of a liquid contained, for instance, in a glass can be sucked away from the same, in that the suction takes place solely at the end proper of the handle where there are the bores *k* and no air can enter into the passage *b* through lateral orifices, as in Fig. 1.

I wish it to be understood that I do not limit myself to the particular constructional forms of valves such as shown in Figs. 2 and 4. Also other constructional valves, suitably designed, may be used for the purpose stated.

I claim:

In a tooth brush in combination with a hollow handle having the inner end open, a hollow rubber bulb having its hollow interior in communication with the opening of the handle associated with said open inner end, the outer end comprising a brush head including tufts of bristles, the outer end of the brush head being provided with several apertures so arranged as to allow passage of water to and between the inner ends of the bristles of the brush head, the outer end of the brush head being also provided with an inlet opening forming a valve seat, and an inlet valve associated with the valve seat in said inlet opening whereby during opening of the valve a quick filling of the brush with liquid is facilitated in a minimum time while on the closing of the valve a strong and continued spray between the teeth is effected.
